UNITED STATES PATENT OFFICE.

GEORGE T. PEARSONS, OF NEW YORK, N. Y.

FIRE-EXTINGUISHER.

1,237,550.

Specification of Letters Patent. Patented Aug. 21, 1917.

Application filed April 5, 1916, Serial No. 89,007. Renewed January 17, 1917. Serial No. 142,959.

To all whom it may concern:

Be it known that I, GEORGE T. PEARSONS, a citizen of the United States, residing in the borough of Manhattan, in the city, 5 county, and State of New York, have invented new and useful Improvements in Fire-Extinguishers, of which the following is a specification.

This invention relates to fire extinguishers in which a fire extinguishing liquid, such as carbon tetrachlorid, is discharged from a reservoir by an expelling agent or gas generated in the reservoir, the production of such gas being the reaction between suitable 10 materials, such as bicarbonate of soda and sulfuric or hydrochloric acid, normally maintained in a separated condition within the reservoir, and one of said materials, preferably the acid, being contained in a 15 fragile receptacle which may be readily ruptured or broken, and when it is desired to utilize the extinguisher such receptacle is broken causing the gas generating materials to mix and generate gas and the expansive force of such gas expelling the 20 liquid from the reservoir; and it is the primary object of the present invention to simplify and improve the general construction of extinguishers of this character to 25 thereby cheapen the cost of manufacture and increase the efficiency thereof.

A further object of the invention is to provide improved means to hold the gas generating materials in a separated condition in the reservoir and such materials with the reacting mixture free from the liquid in the tank.

A further object of the invention is to provide improved means to support the acid carrier and to rupture or break said carrier to cause it to mix with the other gas generating material.

In the drawing accompanying and forming a part of this specification Figure 1 is a sectional side elevation of a fire extinguisher, illustrating an embodiment of my invention.

Fig. 2 is a plan view; and

Fig. 3 is a sectional detail taken on the line 3—3 of Fig. 2 looking in the direction of the arrow, showing the means to maintain the gas generating materials and the reacting mixture free from the liquid in the reservoir.

55 Similar characters of reference designate

like parts throughout the different views of the drawing.

In the embodiment of my invention shown in the drawing a fire extinguishing liquid, such as carbon tetrachlorid, is contained in 60 a reservoir or tank consisting of a body portion 4, preferably cylindrical in shape, closed at one end, as at 5, to constitute the bottom and constructed to form a supporting base for the extinguisher. The upper end is 65 closed by a head 6 having a central opening closed by a removable cover 7. Secured in an opening in the head communicating with the exterior of the reservoir is a discharge tube 8, the said tube extending to adjacent 70 the bottom of the reservoir with such end closed by a check valve closing into and opening outward from the reservoir, as shown at 9. Communication to the exterior of the reservoir through said tube may be 75 shut off by a valve 10 to which is connected by a fitting 11 the usual flexible nozzle tipped hose 12.

Suspended in the reservoir from the opening in the head 6 is a receptacle 13, the said 80 receptacle having a screw threaded connection with said opening whereby it may be removed from the reservoir. This receptacle is adapted to contain a gas generating material, such as bicarbonate of soda, and 85 has an outlet leading into the reservoir. This outlet consists of a tube 14 secured in an opening in the receptacle adjacent the top, as shown in Fig. 3, and is bent at an angle so that the outer end will be in line 90 with an enlarged opening 15 in the reservoir head 6. Communication between the reservoir and the receptacle is shut off by a normally closed valve consisting of a ball 16 coöperating with a valve seat formed in 95 the outer end of the tube 14 and maintained against said seat by a spring 17 engaging at one end with the ball and the other end seated in a recess in a cap 18 removably connected to and closing the opening 15. 100 By this construction access may be readily had to the valve for cleaning or otherwise, and the tube may be removed to permit of the removal of the receptacle 13.

The other gas generating material, or 105 acid, is carried in a receptacle 19, preferably consisting of a thin glass bottle carried by a plunger 20 extending through and having screw threaded or worm connection with the cover 7, the said plunger being sealed in the 110

cover by stuffing boxes 21 and 22 at the outside and inside of the cover. The receptacle 19 is connected to the plunger by a rod 23 of a material which will not be affected by the acid in the bottle, and it may consist of glass, said rod extending into the bottle with the end abutting against the bottom of the bottle and the other end extending out from a restricted portion or neck of the bottle and fixed therein by suitable means which will also serve to seal the bottle as shown at 24, a composition of glycerin and litharge having been found to answer the purpose. The bottle is connected to the plunger through this rod 23 for which purpose the projecting end of the rod is screw threaded, as shown at 25, to have screw threaded connection with a disk or head 26 connected to the end of the plunger by a screw 27.

10 The receptacle or bottle 19 is adapted to engage in a tubular sleeve 28 removably connected to the cover 7 to be suspended therefrom into the receptacle 13 and has a rigid annular abutment or ring 30 fixed to the lower end and against which ring the bottom of the bottle abuts adjacent its lateral edges in its normal position, as clearly shown in Fig. 1.

15 In operation, the parts being in the normal position shown in Fig. 1, the plunger 20 is rotated by a handle or hand wheel 29, and due to its threaded connection with the cover 7, which thread is preferably of a steep pitch, the plunger with the bottle 19 is caused to move downward against the abutment 30 exerting a pressure on the restricted portion or neck of the bottle by the disk 26 and against the bottom of the bottle from the interior by the rod 23 and crushing said bottle, the contents of the bottle dripping onto the soda in the lower portion of the receptacle 13 and immediately generating gas which passes up through the 20 sleeve 28 and out through an opening 31 (Fig. 3) in said sleeve in line with the tube 14 and through the tube 14, the pressure of the gas unseating the valve 16 and passing into the reservoir where the expansive force of the gas will exert a pressure on the liquid in the reservoir; the pressure of the liquid unseating the valve 9 and passing through tube 8 and out through the discharge hose 12. Should a fire be quickly extinguished 25 the flow of liquid may be shut off by the valve 10 and the reservoir relieved of the gas pressure by slightly turning a screw plug 33 which serves to close a filler opening to the reservoir, such turning of the plug connecting the reservoir with the atmosphere through a port 34 in said plug which is normally shut off from the atmosphere by the wall of the filler opening. To readily transport the extinguisher it is provided with a hand grip or handle 35. By

this construction the acid receptacle being carried by the cover is at all times maintained in a fixed position preventing any accidental knocking of the same with the possible breakage as the extinguisher is transported from place to place. Furthermore, the guiding sleeve being removable with the cover may be readily removed for the renewal of the acid receptacle and permit it to be readily cleaned. The screw threaded connection of the receptacle 13 with the head 6 will permit said receptacle to be removed for cleaning and to permit of the cleaning of the interior of the reservoir. The threaded connection of the plunger with the cover serves to lock said plunger against accidental movement in the cover, due to jars or otherwise, and the consequent possible breaking of said receptacle.

Having thus described my invention I claim:

1. In a fire extinguisher, the combination of a reservoir for a fire extinguishing liquid having a discharge outlet and an opening therein; a removable cover for said opening a receptacle suspended from the opening into the reservoir having an outlet leading into the reservoir; a plunger carried by the cover to have movement into the receptacle; and a receptacle carried by said plunger, substantially as and for the purpose specified.

2. In a fire extinguisher, the combination of a reservoir for a fire extinguishing liquid having a discharge outlet and an opening therein; a removable cover for said opening; an open ended receptacle suspended from said opening into the receptacle, said cover also serving to close the open end of said receptacle; a valved outlet leading into the reservoir from the receptacle; a plunger carried by the cover to have movement into the receptacle a receptacle carried by the plunger suspended in the first receptacle; and an abutment against which the latter receptacle is adapted to be forced by the plunger, substantially as and for the purpose specified.

3. In a fire extinguisher, the combination of a reservoir for a fire extinguishing liquid having an outlet and an opening therein; a removable cover for said opening; an open ended receptacle suspended from said opening into the reservoir; said cover also serving to close the opening in said receptacle; a valved outlet leading from the receptacle into the reservoir; a plunger having screw threaded connection with the cover to have movement into the receptacle; a receptacle carried by the plunger suspended in the first receptacle; and a fixed abutment with which the receptacle carried by the plunger is adapted to be engaged at the end opposite to which it is connected to the plunger, substantially as and for the purpose specified.

4. In a fire extinguisher, the combination of a reservoir for a fire extinguishing liquid having a discharge outlet and an opening therein; a removable cover for said opening; an open ended receptacle for a gas generating material suspended from said opening into the reservoir, said cover also serving to close the open end of said receptacle; an outlet leading from said receptacle into the reservoir having a valve opening outward from and closing into the receptacle; a plunger having screw threaded connection with the cover to have movement into the receptacle; an entirely closed receptacle for another gas generating material connected to and movable with the plunger; and a sleeve carried by the cover to extend into the first receptacle and surrounding the second receptacle, said sleeve carrying an annular abutment against which the receptacle carried by the rod is adapted to abut, substantially as and for the purpose specified. 45
5. In a fire extinguisher, the combination of a reservoir for a fire extinguishing liquid having a discharge outlet and an opening therein; a removable cover for the opening; an open ended receptacle for a gas generating material suspended from said opening into the reservoir, said cover also serving to close the open end of said receptacle; a valved outlet leading from the receptacle into the reservoir; a plunger having screw threaded connection with the cover to have movement into the receptacle; a bottle for another gas generating material; a rod extending into said bottle with one end abutting against the bottom of the bottle and sealed in the bottle with the other end projecting therefrom and having screw threaded connection with the plunger; and a fixed abutment against which the bottom of the bottle abuts, substantially as and for the purpose specified. 50
6. In a fire extinguisher, the combination of a reservoir for a fire extinguishing liquid having a discharge outlet and an opening therein; a removable cover for said opening; an open ended receptacle for a gas generating material suspended from the opening into the reservoir and having a valved outlet leading into the reservoir; a plunger having screw threaded connection with the cover to have movement into the receptacle; a head connected to one end of said plunger having a threaded recess; a bottle having another gas generating material; a rod extending into the bottle and sealed in the bottle with the other end screw threaded and projecting from the bottle and adapted to be connected to the threaded recess in the plunger head; and a sleeve carried by the cover to surround the bottle and having an annular abutment against which the bottom of the bottle abuts, substantially as and for the purpose specified. 55
7. In a fire extinguisher, the combination of a reservoir for a fire extinguishing liquid having a discharge outlet and an opening therein; a removable cover for said opening; a receptacle suspended from said opening into the reservoir; a tube to connect the receptacle with the reservoir, one end of said tube being secured in an opening in the receptacle and the other end being in line with an opening in the reservoir and provided with a valve seat; a ball adapted to engage with said seat; a cap to close said opening; a spring carried by said cap to maintain the ball seated in the seat in the tube; a plunger carried by the cover for the reservoir to have movement into the receptacle; and a sealed bottle for another gas generating material carried by said plunger, substantially as and for the purpose specified. 60
8. In a fire extinguisher, the combination of a reservoir for a fire extinguishing liquid having a discharge outlet and an opening therein; a removable cover for said opening; an open ended receptacle for a gas generating material suspended from the opening into the reservoir and having a valved outlet leading into the reservoir; a plunger having screw threaded connection with the cover to have movement into the receptacle; a head connected to one end of said plunger having a threaded recess; a bottle having another gas generating material; a rod extending into the bottle and sealed in the bottle with the other end screw threaded and projecting from the bottle and adapted to be connected to the threaded recess in the plunger head; and a sleeve carried by the cover to surround the bottle and having an annular abutment against which the bottom of the bottle abuts, substantially as and for the purpose specified. 65
9. In a fire extinguisher, the combination of a reservoir for a fire extinguishing liquid having a discharge outlet and an opening therein; a removable cover for said opening; an open ended receptacle for a gas generating material suspended from the opening into the reservoir and having a valved outlet leading into the reservoir; a plunger having screw threaded connection with the cover to have movement into the receptacle; a head connected to one end of said plunger having a threaded recess; a bottle having another gas generating material; a rod extending into the bottle and sealed in the bottle with the other end screw threaded and projecting from the bottle and adapted to be connected to the threaded recess in the plunger head; and a sleeve carried by the cover to surround the bottle and having an annular abutment against which the bottom of the bottle abuts, substantially as and for the purpose specified. 70
10. In a fire extinguisher, the combination of a reservoir for a fire extinguishing liquid having a discharge outlet and an opening therein; a removable cover for said opening; an open ended receptacle for a gas generating material suspended from the opening into the reservoir and having a valved outlet leading into the reservoir; a plunger having screw threaded connection with the cover to have movement into the receptacle; a head connected to one end of said plunger having a threaded recess; a bottle having another gas generating material; a rod extending into the bottle and sealed in the bottle with the other end screw threaded and projecting from the bottle and adapted to be connected to the threaded recess in the plunger head; and a sleeve carried by the cover to surround the bottle and having an annular abutment against which the bottom of the bottle abuts, substantially as and for the purpose specified. 75
11. In a fire extinguisher, the combination of a reservoir for a fire extinguishing liquid having a discharge outlet and an opening therein; a removable cover for said opening; an open ended receptacle for a gas generating material suspended from the opening into the reservoir and having a valved outlet leading into the reservoir; a plunger having screw threaded connection with the cover to have movement into the receptacle; a head connected to one end of said plunger having a threaded recess; a bottle having another gas generating material; a rod extending into the bottle and sealed in the bottle with the other end screw threaded and projecting from the bottle and adapted to be connected to the threaded recess in the plunger head; and a sleeve carried by the cover to surround the bottle and having an annular abutment against which the bottom of the bottle abuts, substantially as and for the purpose specified. 80
12. In a fire extinguisher, the combination of a reservoir for a fire extinguishing liquid having a discharge outlet and an opening therein; a removable cover for said opening; an open ended receptacle for a gas generating material suspended from the opening into the reservoir and having a valved outlet leading into the reservoir; a plunger having screw threaded connection with the cover to have movement into the receptacle; a head connected to one end of said plunger having a threaded recess; a bottle having another gas generating material; a rod extending into the bottle and sealed in the bottle with the other end screw threaded and projecting from the bottle and adapted to be connected to the threaded recess in the plunger head; and a sleeve carried by the cover to surround the bottle and having an annular abutment against which the bottom of the bottle abuts, substantially as and for the purpose specified. 85

GEO. T. PEARSONS.
